Assistant Examiner — Eric N. Welle

(57) **CLAIM**

The ornamental design for a projection floor lamp as shown and described.

DESCRIPTION

FIG. 1 is a front elevational view of a projection floor lamp showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and left side perspective view thereof;

FIG. 8 is a bottom, front and left side perspective view thereof;

FIG. 9 is a top, rear and right side perspective view thereof; and,

FIG. 10 is a bottom, rear and right side perspective view thereof.

The projection floor lamp is shown with a symbolic break in its length. The appearance of any portion of the article between the break lines forms no part of the claimed design.

1 Claim, 10 Drawing Sheets
